UNITED STATES PATENT OFFICE

2,163,704

ELECTRIC IRON AND STAND THEREFOR

Oliver C. Ritz-Woller, Chicago, Ill.

Application November 29, 1937, Serial No. 176,991

4 Claims. (Cl. 219—25)

My invention relates to electric irons and stands therefor and particularly to the type of stand provided with means for feeding current to the iron thereon for heating the iron, and it has for its object the provision of a new and improved form and arrangement of this type by reason of which the sparking when the iron is placed in position on the stand or is removed from the stand may be kept to a minimum as the circuit is alternately made and broken. It is another object of my invention to provide an improved arrangement of parts by reason of which the danger of anyone's receiving an electric shock due to accidental contact with the terminal contact members of the stand is reduced to a minimum. For accomplishing this purpose and for otherwise improving the construction, it is one of the objects of my invention to provide an improved arrangement of closed chamber means within which the sparking is caused to take place so as to smother the spark and also to protect the hands of the operator.

A stand of this type has been provided heretofore, equipped with a fixture plug permanently mounted in position at one end of the stand and having pins or other suitable contact members extending backwardly from its rear face for connection with the usual appliance plug of an electric cord and having its front portion provided with contact members in position to be engaged by the backwardly extending contact members of the iron in normal position on the stand. It is one of the objects of my invention to provide an improved form and arrangement of connections between the backwardly projecting contact members and the contact members at the front portion of such a fixture plug.

It has been one of the objects of my invention to provide an improved arrangement in a plug of this type in which both of the contact members of the plug are adapted to yield backwardly, one of said contact members being arranged to yield to the necessary extent for completing the circuit and the other contact member at the opposite side of the plug being arranged to yield through a considerably greater distance to compensate for the yielding of said first mentioned contact member. It is one of the objects of my invention to provide an improved arrangement of the contact members of the plug together with an improved arrangement of the contact members of the iron whereby I am assured that the initial contact engagement when the iron is put on the stand, and the final contact break when the iron is taken off the stand,

shall always occur at the same side of the plug,—namely, at that side at which the circuit is not broken within the plug.

It is another object of my invention to provide an improved arrangement of yielding contact means through which the circuit is kept complete at all times and in which the spring tending to hold the contact parts in extended position with respect to each other is protected by insulation against the possibility of the current passing therethrough.

It is another object of my invention to improve arrangements of this type in sundry details hereinafter pointed out. The preferred means by which I have accomplished my several objects are illustrated in the drawing and are hereinafter specifically described. That which I believe to be new and desire to cover by Letters Patent is set forth in the claims.

In the drawing,

Fig. 1 is a side face view of a stand and an iron thereon equipped with my improved arrangement;

Fig. 2 is an enlarged detail view of the rear portion of the iron and stand, with certain of the parts broken away and shown in section for clearness of illustration;

Fig. 3 is a horizontal sectional view taken substantially at line 3—3 of Fig. 2;

Fig. 4 is a horizontal sectional view taken on an enlarged scale at the line 4—4 of Fig. 2;

Fig. 5 is a vertical section view taken substantially at line 5—5 of Fig. 4; and

Fig. 6 is a side view of the contact member and spring arm device by which permanent connection is effected through the plug at one side thereof.

Referring now to the several figures of the drawing, in which corresponding parts are indicated by the same reference characters, 10 indicates an electric iron of a type to be supported upon a stand 11 which is positioned normally in slightly inclined position with respect to the table or other level surface upon which it is resting. As is best shown in Figs. 2 and 3, the iron 10 is provided at one end with contact members 12 and 13 in substantially vertical position thereon, from which extend auxiliary contact members 14 and 15 in substantially horizontal position. The contacts 12 and 13 are arranged so as to receive thereon the ordinary appliance plug of an electric cord for heating the iron. An alternative method of heating the iron is carried out through the use of the contact members 14 and 15 as hereinafter described.

In the arrangement shown, my improved iron is provided with a housing 16 formed of sheet metal and open at its rear face, a pivotally mounted hood member 17 being provided adapted to close alternatively either the upper portion of the housing 16 as shown in Figs. 1 and 2 or the lower part of the housing opposite the ends of the contacts 14 and 15.

At the rear end of the stand 11, I have provided a bracket 18 rising from the stand and supporting at its upper end a plug member 19, such plug member in the arrangement shown comprising two body portions 20 and 21 formed of insulation material of any approved type. The body members 20 and 21 are hollowed out at their inner faces to provide two chambers 22 and 23 extending therethrough at the opposite sides of the plug. At the rear face of the plug I have provided contact members 24 and 25 which are mounted rigidly in position at their forward ends in the plug, with shank portions in the form of pins extending backwardly in parallel relation to each other so as to receive thereon the appliance plug 26 of an electric cord 27.

Within the chamber 22 of the plug 19, I have mounted a movable contact member 28 in the form of a pin opposite the contact member 25, such pin 28 having mounted thereon a heavy sleeve 29 of insulating material serving as a sliding support for the pin. A coiled spring 30 is interposed between the insulation sleeve 29 and the contact member 25 for holding them normally in spaced relation to each other. At their adjacent ends, the contact member 25 and the pin 28 are provided with intermediate contact heads 31 and 32, such heads in the arrangement shown being formed of silver in the form of plugs having a pressed fit in oppositely disposed openings in such parts 25 and 28. The arrangement is such that the circuit through the plug 19 from the contact member 25 is normally broken between the intermediate contact heads 31 and 32 but such that when pressure is applied backwardly upon the contact member 28 against the action of the spring 30 such pin 28 moves backwardly for completing the circuit through the plug.

Within the chamber 23 of the plug 19, I have provided a contact member 33 in the form of a cylinder open at its rear end toward the inner end of the contact member 24. Within the cylinder 33, I have provided a block 34 of insulating material forming a seat for a coiled spring 35 which bears at its opposite end against a portion of the contact member 24, serving thus normally to hold the cylinder 33 at the limit of its forward motion. Upon the rear end of the contact member 24, I have mounted a plurality of resilient arms 36 which have sliding engagement within the open end of the cylinder 33 so as to provide permanent electrical connection between the contact member 24 and the contact member 33 while at the same time permitting free and easy movement of the contact member 33 backwardly in the chamber with respect to said contact member 24.

As will be readily appreciated, by reason of the fact that the springs 30 and 35 are seated against blocks of insulating material at their forward ends the electric current passing through the plug 19 is kept away from said springs, being caused to pass at all times through the arms 36 in the one chamber and through the intermediate contact heads 31 and 32 in the other chamber without any danger of said springs becoming heated by the passage of current therethrough.

As will be readily understood, the arrangement of the parts within the chamber 22 as above described is such as to provide a make and break connection through the plug at that side, while the parts at the opposite side of the plug serve as a permanent yielding connection. The arrangement is such that when the contact member 28 is moved backwardly through a short distance the circuit is closed and continued backward movement of the contact 28 thereafter is prevented. The contact member 33 on the other hand is adapted to have backward movement through a considerable distance without affecting the electrical connections at that side of the plug.

As is clearly shown in Fig. 3, the arrangement is such that when the iron is presented evenly to the plug 19 of the stand the contact member 14 is brought into engagement with the contact member 33 appreciably in advance of the engagement of the contact member 15 of the iron with the movable contact member 28 of the plug at the opposite side of the iron and stand. When the contact member 14 of the iron is brought into engagement with the movable contact member 33 of the plug, no spark is produced since the circuit through the plug at the opposite side is still open. No spark is produced either when the contact member 15 is brought into engagement with the movable contact member 28. Upon continued backward movement of the iron, however, the circuit is closed within the chamber 22 and all of the sparking brought about by the closing of the circuit takes place within such chamber. Upon the removal of the iron from the stand, all sparking which occurs again takes place within the chamber 22 since the spring 30 serves to open the circuit between the intermediate contact members 31 and 32 before the contact member 15 of the iron is moved out of engagement with the movable contact member 28. By reason of the fact that the intermediate contact members 31 and 32 are formed of silver and of the fact that the chamber 22 is effectively closed, so as to smother a spark therein, the sparking is kept to a minimum and the parts are protected against pitting or other damage by reason of such sparking.

By the provision of my improved contact member comprising the shank 24 and the resilient arms 36, and the association of such contact member unit with the cylindrical contact member 33 within which the resilient arms have sliding engagement, I am assured that a permanent yielding connection is at all times effected between the members 24 and 33 so as effectively to prevent sparking within such chamber. By this improved arrangement, a connecting means of variable length is provided of such arrangement as to cooperate with the make and break connecting means in the chamber 22, these results being attained without the use of complicated mechanism likely to get out of order even in long continued use.

While I prefer to employ the form and arrangement of parts as shown in my drawing and as above described, it is to be understood that my invention is not limited to the arrangement shown except so far as it may be so limited by the claims, it being understood that changes might well be made in the form and arrangement of parts without departing from my invention.

I claim:

1. In an arrangement of means for feeding current to an electric iron, the combination of two contact members mounted on an iron in

- spaced relation to each other and extending backwardly from the iron, and a cooperating plug mounted on a stand and comprising a body of insulating material, two contact members resiliently mounted at the front face of the plug in position for engagement by the contact members of the iron so as to be moved backwardly in said plug by the contacts on the iron when the iron is moved longitudinally of the stand into normally operative position thereon, two other contact members carried by said body and extending from its rear face in spaced relation to each other for connection with the plug of a cord for feeding electric current to an iron on the stand, means providing a permanent electrical connection between the movably mounted contact member at one side of the plug and the corresponding one of the contact members extending backwardly from the body of the plug, and means providing a make and break connection between the movably mounted contact member at the opposite side of the plug and the corresponding contact member extending backwardly from the body of the plug.
2. In an arrangement of means for feeding current to an electric iron, the combination of two contact members mounted on an iron in spaced relation to each other and extending backwardly from the iron, and a cooperating plug mounted on a stand and comprising a body of insulating material, two contact members resiliently mounted at the front face of the plug in position for engagement by the contact members of the iron so as to be moved backwardly in said plug by the contacts on the iron when the iron is moved longitudinally of the stand into normally operative position thereon, two other contact members carried by said body and extending from its rear face in spaced relation to each other for connection with the plug of a cord for feeding electric current to an iron on the stand, means providing a permanent electrical connection between the movably mounted contact member at one side of the plug and the corresponding one of the contact members extending backwardly from the body of the plug, and means providing a make and break connection whereby the movably mounted contact member at the opposite side of the plug stands normally out of engagement with the corresponding contact member extending backwardly from the body of the plug and whereby an effective electrical connection is established between said members when the movably mounted contact member is moved backwardly to the limit of its motion.
3. In an arrangement of means for feeding current to an electric iron, the combination of two contact members mounted on an iron in spaced relation to each other and extending backwardly from the iron, and a cooperating plug mounted on a stand and comprising a body of insulating material, two contact members resiliently mounted at the front face of the plug in position for engagement by the contact members of the iron so as to be moved backwardly in said plug by the contacts on the iron when the iron is moved longitudinally of the stand into normally operative position thereon, two other contact members carried by said body and extending from its rear face in spaced relation to each other for connection with the plug of a cord for feeding electric current to an iron on the stand, means providing a permanent electrical connection between the movably mounted contact member at one side of the plug and the corresponding one of the contact members extending backwardly from the body of the plug, and means providing a make and break connection between the movably mounted contact member at the opposite side of the plug and the corresponding contact member extending backwardly from the body of the plug, the arrangement of the contact members of the iron with respect to the normal positions of the movably mounted contact members of the plug being such that when the iron is presented evenly to the plug on the stand in the movement of the iron into normal position on the stand the contact member having permanent electrical connections through the plug is engaged by the corresponding contact member on the iron appreciably in advance of the engagement of the contact members at the opposite side of the iron and stand.
4. In an arrangement of means for feeding current to an electric iron, the combination of two contact members mounted on an iron in spaced relation to each other and extending backwardly from the iron, one of said contact members being of appreciably greater effective length than the other, and a cooperating plug mounted on a stand and comprising a body of insulating material, two contact members resiliently mounted at the front face of the plug in position for engagement by the contact members of the iron so as to be moved backwardly in said plug by the contacts on the iron when the iron is moved longitudinally of the stand into normally operative position thereon, two other contact members carried by said body and extending from its rear face in spaced relation to each other for connection with the plug of a cord for feeding electric current to an iron on the stand, means providing a permanent electrical connection between the movably mounted contact member at one side of the plug and the corresponding one of the contact members extending backwardly from the body of the plug, and means providing a make and break connection between the movably mounted contact member at the opposite side of the plug and the corresponding contact member extending backwardly from the body of the plug, the contact members on the iron of differential effective length being arranged so that the longer one of said two contact members engages the contact member of the plug having permanent electric connections through the plug appreciably in advance of the engagement of the contact members at the opposite side of the iron and stand.

C. RITZ-WOLLER.
